UNITED STATES PATENT OFFICE.

EDWARD M. WARING, OF BROOKLYN, NEW YORK.

LONG-KNIFE CLOTH-CUTTING MACHINE.

SPECIFICATION forming part of Letters Patent No. 691,090, dated January 14, 1902.

Application filed March 26, 1900. Serial No. 10,229. (No model.)

To all whom it may concern:

Be it known that I, EDWARD M. WARING, a citizen of the United States, and a resident of Brooklyn, in the county of Kings and State 5 of New York, have invented certain new and useful Improvements in Long-Knife Cloth-Cutting Machines, of which the following is a specification.

This invention relates to an improvement 10 in electric cloth-cutting machines, and particularly to that class of said machine where-in the cutting is done by a reciprocating knife. It may therefore properly be termed a "long-knife cutting-machine," since it operates 15 on the cloth in substantially the same manner as the long knife operated through a slit in the table by hand.

The objects of the invention are the simplification of the driving mechanism for the 20 reciprocating knife both as to the number of parts and as to the mode of operation; also, to so design the parts of the motor and mount the same with respect to the base of the machine that the whole shall be equally balanced 25 over the center of said base.

The invention therefore consists in the construction and arrangement of parts substantially as hereinafter described and claimed.

In the accompanying drawings, which form 30 a part of this specification, Figure 1 represents one form of my machine in side elevation, one of the supporting-brackets for the armature being removed. Fig. 2 is a partly-sectionized front elevation of the machine 35 illustrated in Fig. 1. Fig. 3 is a plan of the standard of the machine. Fig. 4 is a front elevation of a modified form of my reciprocating cutting-machine. Fig. 5 is a partly-sectionized front elevation of a further modification 40 of said machine.

The principal elements of the machine are the standard, consisting of the base J; the column or upright j, to which is attached the handle H; the motor, consisting of the armature A, the field-coils F², the pole-pieces F, and the commutator U; the reciprocating 45 knife P; the cross-head V, and the pitman l for transmitting power from the armature to the knife.

50 Referring to Figs. 1 to 3, the base is provided on its under side with slight projections

M to decrease the area of supporting-surface, and these projections may have mounted in them antifriction-rollers, if desired, this being a common well-known means of supporting cloth-cutting machines intended to travel over the table on which is spread the cloth to be cut. The base is tapered to a thin edge all around and is preferably provided at its forward portion with a still thinner edge 60 formed on a supplemental plate of steel, as illustrated at K, whereby the smooth and ready insertion of the base under the cloth is insured. The column j is made as thin as practicable, and has formed therein a recess 65 the back wall of which is indicated by the line x, and in this recess is guided the knife P. One or more antifriction-rollers, as O, may be mounted in the standard at the back of the recess to furnish a suitable bearing for 70 the rear edge of the knife. The lower end of the knife is made oblique to its forward edge and is sharpened. The forward edge of the knife p' is also sharpened, so that the knife will cut during its upstroke as well as during 75 its downstroke. It is preferable to provide a pressure-foot to keep the lay of cloth down during the upward stroke of the knife. One form of pressure-foot for this purpose is shown at G. This is preferably made vertically adjustable upon the standard. For this purpose it may be provided with a slot, as seen in Fig. 2, and attached to the standard by a suitable thumb-nut, as g³.

The pressure-foot is preferably provided 85 with two branches at its lower end, one, as g, extending along one side of the knife and in front thereof, while the other, g', extends along the opposite side of the knife. It is also preferable to raise the base slightly at the place 90 where the knife enters it, so as to insure a positive cut through the lowermost layer of cloth, and to press said layers more closely together as the knife is about to cut through them. This may be done by means of detachable steel plates forming the raised portion N and the abrupt elevation n at the immediate edge of the slot or recess x into which the knife descends. This construction also provides for the renewal of that part of the 95 base without renewing the whole base.

The upper end of the knife is attached to

- the cross-head V in any suitable way, as by means of the bolt R, which passes into the pin L, the pin L extending through the cross-head and having attached at its opposite end 5 the pitman I. The cross-head V is mounted in a suitable slide or guide q, which is formed in the plates Q Q', these being preferably detachable pieces bolted to the upright j. The lubrication of the guide q should be effected 10 in a manner to prevent lubricant from getting onto the cloth, and for this purpose it is well to provide a layer of felt, as W, at the lower end of the guide. A similar layer W' may also be provided at the upper end of the 15 guide, and a strip of felt or other fibrous material may be placed at the edges of the guide, as indicated at w in Fig. 3. By this means the guide may be well lubricated without the danger of the oil escaping therefrom.
- 20 The motor is mounted upon the flanges j' at the upper end of the standard by screws passing into the cheek-pieces F of the poles of the field-magnets. The cores and pole-pieces of the field-magnets are preferably 25 laminated, as shown at f, and the cheek-pieces are held thereto by suitable screws, as f'. To the cheek-pieces F are secured the brackets B, B' by means of suitable screws passing into holes, as f', in said cheek-pieces. In these 30 brackets are formed bearings for the journals of the armature. To the end of the armature opposite the commutator is secured a disk which carries a counterbalance or balanced lever, as D, from the upper portion of which, 35 as at C, extends the crank-pin c, the opposite end of said pin entering the upper end C' of the balanced lever D'. Upon the crank-pin c is journaled the pitman I. The balanced levers D and D' constitute a counterbalanced 40 double crank. This provides a more stable construction for the support of the crank-pin and at the same time enables the pitman to be brought nearer to the vertical plane of the cross-head, thereby shortening the pin L, projecting from the cross-head.
- 45 One end of the armature-shaft may be extended beyond the bearing and screw-threaded, as shown at s, Fig. 2, to provide a support for the emery-wheel for grinding the knife.
- 50 A cap-nut, as E, may be placed on said screw for protection when an emery-wheel is removed. The bracket B is preferably provided with a downward extension b, which serves as a guard for the lower end of the 55 pitman. The raceway for the cross-head V might be connected to or formed in this extension.
- 60 It will be noted that in the construction just described the field-magnets balance one another over the center of the standard, and the commutator and cranks likewise balance one another and are in the same horizontal plane therewith and removed ninety degrees therefrom. This gives a perfect balance for 65 the motor over the center of the standard and

is the preferred construction. The motor construction, however, substantially as shown in Fig. 4, may be used wherein there is but one field-coil, as seen at Fig. 4. This is mounted between the pole-pieces F, which, as in the 70 previous construction, are bolted to the projections j' at the upper end of the standard. In this form of motor the field and armature are in the same vertical plane and counterbalance one another over the center of the 75 standard. In both forms the center of gravity of the motor is directly over the column j.

The brackets B, B' provide bearings for the journals of the armature and are secured to the poles of the field-coil substantially as in 80 the machine above described. The knife, however, is secured to the cross-head on the side next to the pitman by means of the screw R, substantially as in the other form of machine. The balanced lever D' is of the same 85 form as in the other machine, but has added thereto an auxiliary counterbalance Z, consisting of a screw that may be turned in and out of the counterbalance, and is provided with a suitable jam-nut for holding it in any 90 adjusted position. This provides compensation for the wearing away of the knife. In other details this form of machine is the same as the one first described.

Where it is desired to obtain a greater 95 speed of reciprocation for the knife, an intermediate gear, as Y', may be introduced, as indicated in Fig. 5, this gear being made to mesh with a gear, as Y, secured to the armature A in any suitable way, it being secured 100 in the machine illustrated upon the periphery of the armature. The gear Y' is mounted upon the stud-bearing, as y, and is provided with a balanced crank D, from which extends the crank-pin c. The pitman I connects this crank-pin to the pin L, which passes through the cross-head V. The knife P is secured to the cross-head by the screw R, as before. The motor is preferably of the form shown in Figs. 1 and 2.

110 In none of the machines described have the commutator-brushes been illustrated, it being understood that they are of the ordinary type and suitably secured to the brackets B'.

Other modifications in details of construction besides those above mentioned may be made without departing from the spirit of the invention.

I claim as my invention—

1. The combination with the base, of a recessed column arising therefrom and provided with integral flanges at its upper end, of the motor mounted upon said flanges, the guide secured to the side of the column, the cross-head therein, the knife secured to one side of the cross-head and reciprocating in the recess of the standard, and the pitman secured to the other side of the cross-head and connecting it to the motor, all substantially as set forth.

120

125

130

2. In a cloth-cutting machine, the combination of an electric motor having a balanced crank-pin on its armature, a standard for said motor located directly under the center of gravity thereof and in a plane at right angles to the axis of the armature, a reciprocating knife mounted in a recess in said standard, a guided cross-head to one side of which the knife is connected, and a connection between said crank-pin and said cross-head for reciprocating the latter.
- Signed at New York, in the county of New York and State of New York, this 23d day of March, A. D. 1900.

EDWARD M. WARING.
